UNITED STATES PATENT OFFICE.

RICHARD EDWIN JONES, OF TROY, ALABAMA.

WATCH-HOLDER.

1,264,082.

Specification of Letters Patent. Patented Apr. 23, 1918.

Application filed August 26, 1916. Serial No. 117,822.

To all whom it may concern:

Be it known that I, RICHARD EDWIN JONES, a citizen of the United States, residing at Troy, in the county of Pike and State 5 of Alabama, have invented new and useful Improvements in Watch-Holders, of which the following is a specification.

This invention relates to a watch holder and more particularly to a watch holder 10 which is adapted to serve as a protective casing for a watch when placed therein.

The primary object of the invention is to provide a watch holder of this character wherein a casing comprises a pair of hingedly connected casing sections, with one of 15 the casing sections having mounted thereon a spring pressed winding key which coacts with a lip upon the opposite end of the casing section in retaining a watch within the 20 said casing section when the holder is open.

A further object of the invention is to provide the hingedly connected sections of the casing with inter-engaging latch members of novel construction by means of which 25 the sections of the casing may be held in closed position.

With these and other objects in view, the invention resides in the novel combination and arrangement of parts, which will 30 be hereinafter described and particularly pointed out in the claim.

The preferred embodiment of the invention has been illustrated in the accompanying drawing, although no restriction is necessarily made to the precise details of construction therein shown, as changes, alterations, and modifications within the scope of 35 the claim may be resorted to when desired.

Like characters of reference denote corresponding parts throughout the several 40 views in the drawing, in which:

Figure 1 is a front view of the improved watch holder.

Fig. 2 is a view of the rear side of the 45 watch holder.

Fig. 3 is a side elevation partly in section of the watch holder.

Fig. 4 is a view showing the holder open 50 and one of the casing sections partly in section.

Fig. 5 is a horizontal sectional view through the neck of the watch holder.

Referring now to the drawing in detail, the numeral 1 designates the improved 55 watch holder, the body 2 of which is in the form of a casing formed from any suitable

material such as metal, or the like, and comprises a front section 3 and a back section 4 arranged in opposed relation and hingedly connected, as at 5, to permit swinging movement of the front section 3 upon the back section 4. 50

Each of the sections 3 and 4 has formed thereon a reduced extension 6 which when the sections are in closed position provide 55 the casing or body 2 with a neck 7 in which may be received the winding stem on a watch arranged within the casing and between the sections 3 and 4, with the extension 6 on the front section 3 extending beyond the extension 6 on the back section 4 and provided with a closed end 8 a portion of which when the sections are in closed position closes the open end of the extension 6 on the back section 4. 70

Each section 3 and 4 has arranged therein below the extension 6 thereon a lining 9 adapted to serve as a cushion for a watch when arranged within the casing, said lining 75 preferably being formed from some suitable material, such as rubber, or the like.

The front section 3 has formed thereon above its hinged connection with the back section 4 a lip 9' which when a watch is placed within the front section 4 over-lies a 80 portion of the same and serves to prevent the displacement of the watch from the section 4 when the same is in lowered position.

Headed pins 10 are slidably mounted in openings in the side walls of the extension 85 6 on the front section 3 with each pin yieldably held against movement by a leaf spring 11 arranged within the front section 3 and having one end connected with the inner end of the pin and its other end secured to the 90 front section 3 below its intersection with the extension 6 thereon.

Arranged within the extension 6 on the back section 4 and secured to the side walls thereof are latch bars 12 which when the 100 sections 3 and 4 are in closed position extend within the extension 6 on the front section 3 and engage with the springs 11 which serve as keepers therefor, so that the casing sections may be held in closed position. 105

A housing 14 is secured to the closed end 3 of the extension 6 on the front section 3 and is provided with a closed end 15. A winding key 16 has its shank 17 passed through the housing 14 and provided at one 110 end with a hollow head 18 which is lined as shown. The head 18 is held in engagement

with the winding stem of a watch when arranged within the casing by means of a coiled expansion spring 19 encircling the shank 17 and arranged within the housing 14 between 5 the closed end 15 thereof and head 18 on the shank 17. The lining enables the head 18 to obtain a firm grip on the head on the winding stem of a watch when the key is used to wind the watch, while the spring 19 serves 10 to force the watch firmly against the lip 9'.

The end of the shank 17 which extends beyond the closed end 15 of the housing 14 is provided with an operating head 20.

Through the above described manner of 15 connecting the winding key 16 with the front section 3 of the casing, it will be seen that the spring 19 not only serves to frictionally engage the head 18 with the winding stem of a watch but enables the shank of the winding key to be adjusted within the housing 14 so that watches which differ in size in diameter may be retained within the casing 20 and held therein when the holder is open by the winding key and lip 9'.

25 The back section 4 of the casing has secured thereto a strip of material which is bent to form a hook 21 by means of which the watch holder may be secured to a belt or the like.

30 In order that the watch holder may be connected with an outer garment, the back section 4 has pivotally connected therewith one end of a pin 22, the other end of which is adapted to be brought into engagement 35 with a keeper 23 on the back section thus enabling the watch holder to be quickly and easily connected with or removed from an outer garment, or the like, when desired.

When it is desired to use the watch holder, pressure is applied to the heads 12 on the 40 pins 10 to release the springs 11 from engagement with the latch bars 13 so that the front section 3 of the casing may be moved to open position.

The watch to be associated with the holder 45 is now arranged within the front section 3 and the hollow head 18 engaged with the winding stem thereof to retain the watch engaged with the lip 9'.

The front section 3 is now swung to a 50 closed position at which time, the latch springs 11 engage with the keepers 13 and hold said sections in locked position.

The holder may now be connected with a belt by means of the hook 21 on the back 55 section 4 or may be secured to an outer garment by means of the pin 22, it, of course, being understood that both the hook 21 and pin 22 may be used for this purpose if desired. 60

Having thus described the invention, what is claimed as new, is:

The combination with a watch, of a casing therefor comprising a pair of hingedly connected casing sections, between which said watch is received, a stem slidably mounted in one end of one of said casing sections yieldably held in engagement with the winding stem on the watch, and an inclined lip at the other end of said casing section beneath which said watch extends adapted to coact with said slidably mounted stem in retaining the watch within the said casing section when the casing is opened. 65 70 75

In testimony whereof I affix my signature. 75
RICHARD EDWIN JONES.
